UNITED STATES PATENT OFFICE

ALBERT C. FISCHER, OF CHICAGO, ILLINOIS, ASSIGNOR TO THE PHILIP CAREY MANUFACTURING COMPANY, A CORPORATION OF OHIO

RAIL FILLER

Application filed August 21, 1926. Serial No. 130,688.

My present invention relates in general to paving and the like projects, and has particular reference to a means for insulating the rails of car tracks when the same are embedded in city streets and other like places, where it is desirable to muffle noise as much as possible, and also absorb vibrations so as to protect the paving material, and also compensate for expansion and contraction of the rails and the paving material.

When I refer to insulating material or insulating means it should be considered that I have in mind insulating against noise as well as against vibration, and also against expansion and contraction. In other words, the material forming the basis for my present invention is capable of acting in this capacity in the most acceptable manner.

One of the objects of my invention resides in providing rail fillers of relatively short sections adapted to be inserted between the head and base of a rail, and wherein each section is provided with a weakened portion, such for instance, as a groove, whereby the section may be hammered into position because of the yielding nature of the section due to the groove, and which groove is adapted to receive an interlocking member, the arrangement being such that the interlocking member will interconnect the adjacent sections, whereby not only to hold them in position but also to hold each section tightly in position between the head and base of the rail.

To clearly describe my invention I will refer to the preferred embodiment of the same illustrated in the accompanying drawing, in which Figure 1 is a perspective view of a section of an ordinary T-head rail, illustrating the application of my invention thereto.

Figure 2 is a detailed perspective view of two abutting sections of the material forming a part of my invention.

Figure 3 is a perspective view of a section of wedge used in combination with the material.

Figure 4 is a perspective view of a section of rail and paving material in which the rail is imbedded and illustrating the application of my invention.

For the sake of convenience I will refer to the material as a rail filler, and in constructing the same I prefer to make the filler in preformed sections 5, which, when installed along one or both sides of the rail 6 will usually be arranged with the ends of the sections in abutting relation as at 7. Each section will be preformed to correspond to the spaces along the rail web 8 that it is adapted to fill. The upper edge 9 of each section will conform to the shape of the underside of the rail head 10, and the lower edge 11 of each section will be made to conform to the top side of the rail base 12. For the most part the outer sides of the sections will be made perpendicular and the thickness of the same should at least be sufficient to present the outer wall flush with the side of the rail head 10.

The shape of the preformed sections may be modified in the event that the filler is used with rails having flanged heads, but such modifications in the design in no way affects the principle of the invention. For this reason I have not thought it necessary to show the filler in combination with anything more than an ordinary T-head rail.

The preformed sections of filler may be made from any material suitable for the purpose, and as an acceptable composition I would suggest a mixture of oxidized asphalt, having incorporated therein fibrous material, such as, roofing scrap (which for the most part is nothing more than saturated felt, although containing gritty particles or some lime stone), sawdust, ground corn cobs, shoddy dust, or any other such materials to make up a more or less readily deformable, compressible mass, having the inherent qualities of compensating for expansion and contraction, absorbing shocks, vibrations, capable of deadening sound and, of course, being waterproof.

The most convenient method of preforming the sections would be an extruding machine, and for this reason in selecting a mixture care should be taken that a composition is decided upon that can be accommodated by an extruding machine. Of course this is not important since the sections could be otherwise molded, but not to as good advantage as

would be produced by an extruding machine.

The composition referred to in a co-pending application Serial Number 79,543, filed January 6, 1926, for the same general class of invention, would be acceptable for turning out the sections of the present invention.

In installing the sectional filler it should be set in place with sufficient force to make it snugly fit the spaces in the rail, in fact it should be wedged in place. Not relying on this snug fit to retain the sections intact I propose to interlock the same with sections of wooden strips 14, the same being bevelled along the opposite longitudinal edges 13 and 15, so as to fit the dove-tailed recesses 16 in the sections 5 of the filler.

I ordinarily prefer to arrange the strips 14 in each section of filler, so that the abutting ends 17 of the strips will overlap the abutting ends of the filler sections. In applying the strips 14 they would be slipped in the end of the recesses and driven in the same until the end of one section abuts the end of a previously driven section, indicated as at 17. This arrangement will interlock the sections 5 together and hold them in alignment, and also aid the wedging effect to hold them snugly in place. The use of the wooden strips also serves as an abutment for the paving material, which in the present illustration is shown as blocks 18.

The perpendicular walls along the rail made by the sections of filler present a surface outward to the paving, for instance, the blocks 18 and the wooden strips act as a reinforcing means so as to prevent sagging of the filler and thus holding the paving in alignment.

While I have shown and really described the filling material applied to opposite sides of the rail, in some instances, it may be only necessary, or even only possible to apply the same to one side. However, the sections function the same on one or both sides.

45 I claim:

1. A rail filler comprising a preformed section of a ductile compressible material, constructed and arranged to be inserted in position between the head and base of the rail, said section having a weakened portion so as to permit the sections to yield when hammered into said position, said weakened portion being shaped to receive a reinforcing member, which, when in position, will be interlocked therein and lock said section in position between the head and base of the rail.

2. A rail filler comprising preformed sections of ductile material, adapted to be positioned between the head and base of a rail and in registration with the adjacent ends of the sections abutting, each section having a weakened portion extending longitudinally thereof, with the weakened portions registered, whereby to assist in positioning the sections between the head and base of the rail,

and an interlocking member adapted to be inserted and positively secured in said weakened portions for interlocking said sections.

3. In combination with a rail having a head and a base projecting from the side surface of the rail, rail filler sections of compressible material, said sections being formed with means for permitting temporary deformation of said sections to facilitate their positioning between the head and base of the rail, and a member adapted to be positively associated with said deforming means, whereby to lock adjacent sections in position and together.

4. In combination with a rail having a projecting head and a projecting base, rail filler sections of yieldable material, and having registering portions adapted to permit the facile deformation of said sections to permit their positioning between the head and base of the rail adjacent one another, and with their ends substantially abutting, and a member of relatively noncompressible material adapted to interlock with the registering portions of said member to lock them in such position and to lock them together.

5. In a rail filler the combination of a plurality of grooved sections and a reinforcing strip engaging the grooved portions of adjacent sections to positively interlock the sections and bind them in position in the rail.

6. In a rail filler the combination of a plurality of filler sections comprising preformed blocks of bituminous material having longitudinal grooves formed therein and shaped to conform with the sides of a rail and reinforcing strip engaging the grooved portions of adjacent filler sections to positively interlock said sections and secure them to the rails.

7. In a rail filler the combination of a plurality of grooved filler sections comprising preformed blocks of bituminous material shaped to conform with the sides of a rail and a reinforcing strip engaging the grooved portions of the sections to lock them together and to the rail, said grooved portion being in the form of a dovetail groove whereby upon insertion of the strip in a filler section, it may be expanded to have firm engagement with the rail.

8. In a rail filler the combination of a plurality of grooved filler sections each comprising a preformed material, shaped to conform with the sides of a rail, a reinforcing strip positioned in the grooved portion of adjacent sections, said grooved portion being formed in the shape of a dovetail groove and said strip extending in the grooves of adjacent sections.

9. In combination a rail filler, said rail filler comprising a plurality of grooved filler sections shaped to conform with the sides of a rail and having a dovetail groove formed therein and a reinforcing strip arranged in the grooves of adjacent sections.

10. In combination a rail, a plurality of rail filler sections comprising preformed blocks of bituminous material shaped to conform with the sides of a rail and having a longitudinal groove formed therein and a reinforcing strip seated in said groove for the purpose of positively interlocking said sections and binding them together.

5 11. A rail filler comprising a preformed slab of ductile compressible material, constructed to be inserted in the cavity adjacent the web between the head and base of a rail, said filler being grooved on one face to provide a recess in which a positively interlocking means may be inserted.
